US0D1047224S

(12) **United States Design Patent** (10) Patent No.: **US D1,047,224 S**
 (45) Date of Patent: ** Oct. 15, 2024

(54) **WINDOW WALL SYSTEM FRAME PROFILE**

(71) Applicant: **ASAS ALÜMINYUM SANAYI VE
TICARET ANONIM SİRKETİ,
İstanbul (AR)**

(72) Inventor: **Safa Bayar Yavuz, İstanbul (TR)**

(**) Term: **15 Years**

(21) Appl. No.: **29/842,859**

(22) Filed: **Jun. 16, 2022**

Related U.S. Application Data

(62) Division of application No. 35/511,159, filed on Dec. 29, 2020 (U.S. filing date under 35 U.S.C. 384), and having an international filing date of Dec. 29, 2020, now Pat. No. Des. 960,392.

(57) **CLAIM**

The ornamental design for a window wall system frame profile as shown and described.

DESCRIPTION

The sole FIGURE is a perspective view of a window wall system frame profile showing my new design.

The broken lines represent the bounds of the claimed design, and form no part of the claimed design.

1 Claim, 1 Drawing Sheet
